UNITED STATES PATENT OFFICE.

DANIEL H. TWAITS, OF CHICAGO, ILLINOIS.

GREASE-CUP.

1,200,548.

Specification of Letters Patent. Patented Oct. 10, 1916.

Application filed March 4, 1914. Serial No. 822,309.

To all whom it may concern:

Be it known that I, DANIEL H. TWAITS, a citizen of the United States, residing at Chicago, in the county of Cook and State 5 of Illinois, have invented a certain new and useful Improvement in Grease-Cups, of which the following is a full, clear, and exact description, reference being had to the accompanying drawings.

10 This invention relates to grease cups of a type having a body portion and a cap carried by the body portion adapted to be moved toward the same for forcing grease from the body portion to the bearing surfaces.

An object of the invention is to provide a locking device for securing the cap to the base and for holding the same in the position last given it, while allowing the device to be released to move the cap on the base or to remove it therefrom by means extending outside the cap.

More specific objects are to so construct such a locking device that it will securely hold the cap on the base and prevent relative movement of the same until released by hand, and to provide a grease cup which shall be strong, durable and efficient in service.

30 My invention is hereinafter more fully described in connection with the accompanying drawings and the essential characteristics are set forth in the claims.

Figure 1 is a side elevation of my grease cup; Fig. 2 is a central vertical section through the same showing the locking device; Fig. 3 is a horizontal section taken on the line 3—3 of Fig. 2; Fig. 4 is a side elevation of a modified form of my grease cup; Fig. 5 is a central vertical section through the same; Fig. 6 is a horizontal section taken on the line 6—6 of Fig. 5; Fig. 7 is a side elevation of another form of my grease cup; Fig. 8 is a vertical central section of the same showing a modified construction of the spring locking device; Fig. 9 is a horizontal section taken on the line 9—9 of Fig. 8; Fig. 10 is a side elevation of still another form of my grease cup; Fig. 11 is a vertical central section through the same and Fig. 12 is a horizontal section taken on the line 12—12 of Fig. 11.

Referring to Figs. 1, 2 and 3: 1 indicates a base and 2 a cap, vertically slidably thereon. The base comprises a hollow stem

4, having a reduced external threaded portion 5 at its lower end and having an outwardly pressed bead 7 near its upper end engaging the lower side of an intermediate offset disk extending through the central opening in this disk and through a disk 9 being upset at 11 to securely hold these disks in place. The offset portion of the disk 8 provides an annular groove in which is carried a resilient ring 12 of leather or other suitable material, for preventing the leakage of grease past the head.

The cap itself is preferably cylindrical as shown, and slidably fits over the periphery of the disks 8 and 9, and the resilient ring. This cap contains the grease which is adapted to be forced through the hollow stem 4 to the bearing surfaces, by pushing the cap down over the head. Carried by the cap are two depending spring members 14 having downwardly extending portions 15 forming projections 16 adapted to engage notches or horizontal corrugations 18 on the interior of the stem.

Below the projections 16 the spring members extend inwardly on an angle at 19, and then downwardly as at 20. The angle of portions 19 is such that a cross member 22 having a slidable engagement with the lower end of the spring members, may draw the projections 16 out of engagement with the notches on being pulled upwardly.

The cross member is provided with two lateral slots 23 slidably engaging the springs and is adapted to be raised by a slidable rod 25 rigidly secured thereto at its lower end, extending through the top of the cap and provided at its upper end with a ring 26. This ring is slidable in two sides of a U-shaped wing 27 having outwardly extending feet 28 riveted to the top of the cap. This wing is preferably made of a flat strip of metal bent in the form of a U and having vertically extending portions 29 which form inwardly opening grooves engaging the sides of the ring 26.

To prevent the leakage of grease past the rod 25, where it passes through the top of the cap, I provide a resilient packing 30, surrounding this rod beneath the top of the cap, and hold the same in place by a washer-like disk 31 having downwardly turned portions 32 to conform to the shape of the top of the cap. The spring members 14 extend outwardly as at 34, and have downwardly

turned ends 35, to conform to the washer-like disk. These spring members, the washer and the wing 27 may be rigidly secured to the cap by rivets 36, as shown.

5 The portions of the spring members above the outward projections are preferably made trough-shaped, which greatly strengthens them, and prevents them being distorted when the cross member 20 is slid 10 upwardly.

By grasping the ring 26, the slide 20 may be raised drawing the projections out of engagement with the notches and thereby allowing the cap to be moved vertically on the 15 base. In case it is desired to compress the grease, forcing it through the stem by pressing downwardly on the cap, this may be conveniently done by placing one finger through the ring 26, grasping the top of 20 the wing or yoke 27, thus the ring may be readily moved, drawing the projections 16 out of engagement with the notches, thereby unlocking them, and then pressing downwardly with the thumb to move the cap 25 down. It will be seen that by making the lower portions of the spring members vertical and parallel as shown, that when the cross member is in its normal position, shown in Fig. 2, the lower ends of the spring 30 cannot be moved toward each other, as the cross member prevents them. Accordingly, the projection cannot be moved inwardly out of engagement with the notches, and the cap is thereby locked at all times, except 35 when the ring 26 is moved upwardly.

Referring to Figs. 4, 5 and 6: In this form of construction the base 1 is provided with a hollow stem which is integral at its 40 upper end with an outwardly extending disk 40, beneath which is a resilient member 41 corresponding to the ring 12 and supported by a washer-like disk 42 resting on a sleeve 43 surrounding the exterior of the stem 4 of the base.

45 At the lower end the stem is provided with threads 45 above which is a shoulder 46 and an angular internally threaded member 47 screwed onto the threads 45 securely presses a disk-like bottom 44 of a cup-shaped 50 housing 55 upwardly against the shoulder 46 thereby holding the housing. At the same time this presses upwardly on the sleeve 43, securely holding the disk 42 and resilient washer 41 in place. The member 47 is provided with external threads 48 adapted to 55 be secured into the member to be lubricated and it is prevented from becoming loosened on the threads 45 by means of a pin 49 extending upwardly and engaging the member 60 47 and threaded portion 45.

The cap 2 is fitted over the enlarged head formed by the disks as described. It is vertically slidable thereon and fits into the housing 55 thereby preventing dust from 65 working its way to the interior of the cup.

This cap is securely held in position by spring members 50 acting on the same principle as the springs in the form first described, said spring members having outwardly extending portions 51 and 53 forming 70 projections 52 adapted to engage notches or horizontal grooves 54. The portions 53 have a connecting loop 56 tending to move the projecting portions outwardly thereby causing a yielding engagement with the 75 notches.

At their upper ends the spring members are bent outwardly as at 57, resting against the bottom of a washer 58 having an upwardly turned flange 59 engaging the top 80 of the cap. Within this washer 58 is resilient packing material 60 adapted to prevent the leakage of grease past a vertically 85 slideable rod 62. The ends 57 of the springs and the washer 58 are secured in place in any suitable manner, as by rivets 63 as shown.

The vertically slideable rod 62 has at its lower end a cross slide 65 having slots engaging the spring members and adapted 90 when depressed to engage the projecting portions 51 and cam the projections 52 inwardly against the action of the spring portion 56, thereby allowing the vertical movement of the cap. At the upper end of the 95 rod 62 is provided a suitable button-like member 66 which may be depressed by hand to release the projections 52 and allow the movement of the cap.

When it is desired to force the grease 100 from the interior of the cup, it is only necessary to press downwardly on the button 66. This releases the locking device as described, and allows the cap to be pulled downwardly through the rod 62 and the 105 spring members, thereby forcing grease through the stem and to the bearing surfaces. As soon as the pressure is released from the button 66, the projections again engage the notches on the interior of the 110 stem and hold the cap in the position last given it. To remove the cap, it is only necessary to grasp an outwardly extending knurled bead 68, at the upper portion of the cap, with two fingers, depressing the button 115 66 with the thumb and pulling upwardly on the cap.

Referring to Figs. 7, 8 and 9: In this form of construction the stem 4 of the base has a cylindrical interior 70, and a hexagonal exterior 71. The head of the base is constructed as described in the first form, with the disk 9 and the resilient member 12 secured in place by an offset washer-like disk 8, both of these disks being held by upsetting the stem. In this form the cap 2 is adapted to be locked into position on the base member by means of a spiral spring 73, having one end threaded through a hole at 74, in the lower end of a strut 75. The 130

upper end of this strut is turned outwardly at 76 fitting against the under side of a washer-like disk 78, above which is provided packing 79, preventing the leakage of grease past a vertically slidable rod 80, extending through the top of the cap.

The upper end of the spring 73 is secured to the lower end of the slidable rod 80 by threading through a hole at 82. The diameter of the spring 73 is such that when the spring is elongated, it will be small enough to allow it to be slid vertically within the stem, but when it is allowed to contract by its own spring action, it increases its own diameter sufficiently to very tightly engage the cylindrical surface of the interior of the stem, thereby securely holding the cap in the position last given it.

To conveniently elongate the spring to thereby release its engagement and allow the vertical movement of the cap, I secure to the upper end of the slidable rod 80, a ring 84, which may be grasped by the fingers to raise the rod 80, elongate the spring and release its engagement, as described. I prefer to provide a wing or yoke 27 as heretofore described, over this ring 84, the same being secured to the cap in any suitable manner, as by rivets 85 and 86, passing through the disk 78, the rivets 86 passing also through the portion 76 of the strut 75, thereby securing all these parts in position.

The operation of this form of cup is similar to that of the first form described, it being only necessary to grasp the ring 84 and raise the same and then move the cap downwardly to force out the grease, or upwardly to remove the cap, as desired.

If desired, outwardly extending grooves 88 may be provided on the interior of the cap by pressing outwardly the ribs 89, as shown. The grooves being engaged by projections 90 on the periphery of the disks 8 and 9, provides a guide for the cap. These guides may be provided as shown in any of the forms herein described. In the form shown in Figs. 4, 5 and 6, the housing 55 has vertical grooves 91 complementary to the ribs 89.

Referring to Figs. 10, 11 and 12, in this form the base 1 is constructed exactly the same as that just described, and the locking device comprises a spring member 94 corresponding to the spring member 73 adapted to lock the cap onto the base to hold the same in the position last given it, but being operated by a vertically slidable rod 95 secured to the lower end of the spring and adapted to elongate the same when depressed, the other end of the spring being brought upwardly at 96 and secured at 97 by means of a rivet 98 to the top of the cap. The upper end of this rod 95 is provided with a button 66 by which the rod may be depressed to elongate the spring,

suitable packing 60 being provided, and held as described in connection with Figs. 4, 5 and 6. The cap is also provided with a knurled bead 68 which may be grasped by the fingers, while the button 66 is depressed by the thumb to remove the cap from the base.

It will be seen from the foregoing description that I have provided a grease cup the cap of which may be readily locked by my locking device, to the base member, and that such a cup may be very simple and cheaply constructed, while being quickly and efficiently operated.

It will be particularly noted that I have provided a grease cup which except for the threads at the lower end of the stem, can be made without any threading operations.

The cup may be very largely made by pressing operations, which it is generally known, are much cheaper and more advantageous in many ways than machine operations.

Having thus described my invention, what I claim is:

1. In a grease cup the combination of a base, a cap slidable over said base, a spring carried by the cap and adapted to expand and engage the interior of the base, and means extending outside the cup and adapted to be moved by hand for releasing the grip of the spring within the stem allowing the movement of the cap.

2. In a grease cup the combination of a base having a head and a hollow stem, a cap movably carried by said head, a spring carried by the cap and extending into said stem and adapted to expand and engage the interior surface thereof, and means carried by the cap engaging the lower end of the spring adapted to be manually operated to release the engagement of the spring with the stem.

3. In a grease cup the combination of a base having a head and a hollow stem, a cap vertically slidable on said head, a spring carried by the cap extending into said stem adapted to engage the same, and a vertically movable member carried by the cap engaging the lower end of the spring and extending outside the cap adapted to be manually operated to release the grip of the spring within the stem thereby allowing the movement of the cap.

4. In a grease cup the combination of a base member having a hollow interior, a cap movably carried by said base, a spring carried by the cap and extending within the base and adapted to engage the interior thereof to hold the cap in the position last given it, and a vertically slidable member extending upwardly through the top of the cap and engaging the lower end of the spring adapted to be depressed to cause the spring to release its engagement with the

interior of the base allowing the removal of the cap.

5. In a grease cup the combination of a base having a hollow interior, a cap member vertically slideable over said base, spring members carried by the top of the cap extending into said base and adapted to expand into engagement with the interior thereof, a vertically slideable rod carried by 10 the cap, means on the lower end of said rod co-acting with the lower end of the spring whereby a longitudinal movement of the rod causes the engagement of the spring to be released, and means on the outer end 15 of the rod to be grasped by the hand.
6. In a grease cup the combination of a base member having a hollow interior, a cap vertically slideable on said base member, a spring member having two substantially 20 parallel depending portions extending into the base and secured at their upper ends to the cap and having outward projections at their lower ends, a vertically slideable member engaging said projections, and means 25 outside the cap adapted to be grasped by the hand to move said projections inwardly.
7. In a grease cup the combination of a base member having a hollow interior, a cap member vertically slideable thereon, a spring locking device secured to the cap member having depending portions extending into the base, portions projecting at an angle from the lower end of the depending portions, a member slideable on said depending 30 portions, and adapted to engage the projecting portions, and a vertically slideable member extending outside the cap whereby the grip of the spring may be released.

8. In a grease cup the combination of a 40 base member having a hollow interior, a cap member vertically slideable on said base member, spring members attached at their upper ends to the cap extending into the base having projections engaging the interior of 45 the base, a member slideable on said spring members and adapted to engage said projecting portions, a rod extending outside the cap, and a means on the end of the rod

adapted to be grasped by hand to move said slideable member to release the spring. 50

9. In a grease cup the combination of a base member having a hollow interior provided with notches, a cap member vertically slideable over said base member, a pair of spring members carried by the cap and extending into said base having projections engaging the notches, and a connecting portion causing said projections to spring outwardly, a member slideable on said spring members adapted to be operated from outside the cap to cause the release of said projections. 55

10. In a grease cup the combination of a base member having a hollow interior, a cap vertically movable on said base member, a spring carried by the cap and extending into said base and adapted to engage the interior thereof, and vertically movable means carried by the cap and adapted to be depressed to cause said spring to release its engagement with the base. 60

11. In a grease cup, the combination of a base member, a cap member movably mounted thereon, laterally expandible means carried by one of said members and adapted 75 to engage the other to prevent relative movement, and means extending outside of the cup and connected with the last mentioned means for contracting said expandible means to cause it to release its engagement. 80

12. In a grease cup, the combination of a base member, a cap member slideable over the base member, said base member having a hollow interior, an expandible means carried by the cap and adapted to engage the 85 interior of the base, a movable member connected with said expandible means and extending through the cap and adapted to be depressed to release the engagement of the expandible means. 90

In testimony whereof, I hereunto affix my signature in the presence of two witnesses.

DANIEL H. TWAITS.
